UNITED STATES PATENT OFFICE.

EDWIN L. HARMON, OF GROTON, NEW YORK, ASSIGNOR TO AMERICAN ROAD MACHINERY COMPANY, INC., OF KENNETT SQUARE, PENNSYLVANIA, A CORPORATION OF DELAWARE.

ROAD-OILER.

1,233,875.

Specification of Letters Patent. Patented July 17, 1917.

Application filed December 8, 1916. Serial No. 135,751.

To all whom it may concern:

Be it known that I, EDWIN L. HARMON, a citizen of the United States, residing at Groton, county of Tompkins, and State 5 of New York, have invented a new and useful Improvement in Road-Oilers, of which the following is a full, clear, and exact description, reference being had to the accompanying drawings, which form a part of this 10 specification.

My invention relates to vehicular machines, sometimes called road oilers, for distributing bituminous and binding material upon roads. The main object of the invention 15 is to provide readily adjustable means for governing the lateral position of the transversely extending row of nozzles through which the material is discharged.

The drawings show preferred embodiments of the invention, in which:—

Figure 1 is a rear view of my improvement.

Fig. 2 is a plan view of the same;

Fig. 3 is a side view of the same;

25 Figs. 4 and 5 are views, similar respectively to Figs. 2 and 3, showing a modification.

In describing the invention, I shall omit references to more or less necessary parts 30 of the machine that do not intimately coöperate with the parts embodying the invention, which relates solely to the pipe construction between the supply tank and the nozzles.

35 The supply tank *a* is supported from the vehicle body in any known way. Extending downwardly and rearwardly from the tank is a pipe *b* which, through a pump *c*, communicates with an upwardly extending pipe *d*.

40 Swiveled on the pipe *d* is a rearwardly extending pipe *e*, which in turn is swiveled on a downwardly depending pipe *f* secured to the center of a transversely extending 45 tributer pipe *g*. The connections between the pipe *e* and the upright pipes *d* and *f* are preferably afforded by means of elbows *h* at opposite ends of the pipe *e* which turn respectively on the axes of the pipes *d* and *f*.

50 The opposite ends of pipe *g* turn downward, the downward extensions *h* being screw-threaded in nozzles in two transversely extending alining pipes *i* provided with discharge nozzles *j*.

The nozzle pipes *i* extend in a horizontal 55 direction parallel with the axis of the wheels. It is desirable to provide for adjusting these nozzle pipes in a lateral direction so as to bring within range of distribution areas of roadway considerably to one side or the 60 other of the vehicle wheels. The above described construction permits this lateral adjustment to be effected by a transverse bodily movement of the pipe *g*. As the pipe *f* moves with the pipe *g*, the rear end of the 65 pipe *e* is carried along with it, the forward end of pipe *e* swinging on pipe *d* on the latter's axis. The lateral movement of pipe *g* shortens the distance, measured in a line at 70 right angles to the axis of the vehicle wheels, between pipes *d* and *g*, and consequently the two fixed supports and guides *m* for the pipe *g* are slotted to admit of a bodily rearward movement of the pipe *g*. As the pipe *g* and the nozzle pipes *i* are 75 adjusted laterally, they may not at all times occupy a position of precise parallelism with the axis of the wheels, although they can depart but slightly therefrom; but such exact parallelism is unimportant, it being obvious that in any lateral adjustment of the nozzle pipes they will maintain their position of parallelism with the roadway and be at all times the same distance above the 80 roadway.

85 A pronounced advantage of the foregoing construction is that only two swiveled pipe connections are required, thus simplifying the structure by diminishing the number of joints.

90 In the modification shown in Figs. 4 and 5, the construction is the same as that above described except that the two supports and guides *n* for the pipe *g* are not slotted and that the pipe *o* (corresponding to pipe *e*) 95 has a telescopic connection with the elbow *p* swiveled on pipe *f*. In this construction the lateral movement of the pipe *g* and the nozzle pipes *i* causes the rear end of pipe *o* to move in the direction of its length within 100 its seat in the elbow *p*, and the nozzle pipes *i* will at all times maintain a position of exact parallelism with the axis of the wheels.

105 The guides *m* or *n* and the hanger *r* for the pump are suspended from the main frame *s* of the machine. The wheels *t* are shown in dotted lines.

I have referred to the screw-threaded connections between the depending extensions *h* of the distributor pipes *g* and the nozzle pipes *i*. Ordinarily this connection is a rigid one, but if either of the nozzle pipes strikes an unyielding obstruction, the nozzle pipe will turn on the threads of the corresponding pipe *h* and permit the vehicle to go ahead without damaging the pipe structure. To permit this operation the two nozzle pipes are made separate, although they can be made as a single pipe if it is cared to assume the risk of injury from striking an obstruction.

Having now fully described my invention, what I desire to claim and protect by Letters Patent is:

1. In a machine of the character described, the combination with a transversely movable distributor pipe and extensions at opposite ends thereof, of two parallel upright pipes, one disposed behind the other, whose upper ends are at a common level, a swinging radius pipe, means including swiveled connections connecting opposite ends of the radius pipe with the upper ends of the two upright pipes, a supply tank, a pipe connection extending therefrom having a rear upturned end extending toward the front upright pipe, a pump interposed between and communicating with said rear upturned end of the tank pipe and the lower end of the front upright pipe, and two separate nozzle pipes swingable on the axes of, and secured between their ends to, the respective extensions of the distributor pipe, the inner ends of the two nozzle pipes closely approximating.

2. In a machine of the character described, the combination with a supply tank, of a supply pipe communicating with the supply tank, a transversely movable nozzle pipe structure, guides permitting the latter to move transversely but restraining it from moving forwardly or backwardly, a swinging radius pipe located between the supply pipe and the nozzle pipe structure, and means, including swiveled connections and a telescopic joint, connecting the radius pipe with the supply pipe and the nozzle pipe structure.

3. In a machine of the character described, the combination with a laterally movable distributor pipe and extensions at opposite ends thereof, of a supply tank, a pipe communicating with the supply tank, a swinging radius pipe, means including swiveled connections connecting opposite ends of the radius pipe with the other two pipes, and two separate nozzle pipes, each secured between its ends to one of said extensions of the distributor pipe, the inner ends of the two nozzle pipes closely approximating and the outer ends thereof extending a substantial distance beyond said extensions, said nozzle pipes being screw threaded to said extensions in such direction as to permit the outer end of either pipe to swing backwardly when encountering an obstruction but affording otherwise a substantially rigid connection with said extension.

In testimony of which invention, I have hereunto set my hand, at Groton, N. Y., on this 28 day of November, 1916.

EDWIN L. HARMON.
